ELECTRIC TIME SWITCH

Joel Henry Hendrix, New Castle, Pa.

Application April 23, 1940, Serial No. 331,252

10 Claims. (Cl. 200—36)

Generically this invention relates to time controlled electric switches operable to open or close an electric circuit as desired but it is more especially directed to the type adapted to be mounted as a unit on a conventional alarm clock without in any way changing the structural arrangement of the clock.

One of the principal objects of this invention is the provision of an automatic electric time switch of the rotary type adapted to be installed on an alarm clock and adapted to operate in conjunction with the alarm mechanism without affecting the normal winding or unwinding operations of the mechanism and without affecting the sound of the alarm.

An important object of this invention is the provision of a time switch of the above character adapted to be operated at a predetermined time by the alarm mechanism, including a sectional shaft structure for connection with the ordinary alarm winding shaft, thereby permitting use of the alarm winding key to effect winding of the alarm mechanism in its normal manner without regard to the switch mechanism, and means for mounting the switch mechanism on the clock without deadening the sound of the alarm and attachable by fastening means carried by the clock without affecting their normal functioning.

Another important object of this invention is the provision of a time controlled rotary switch of this character having settable arrestor elements for stopping or releasing the alarm winding means to open or close an electrical circuit to turn on or off electric lights, radios and different types of electrical appliances, and to control the starting and stopping of motors and the like, as desired.

A still further important object of this invention is the provision of a time control switch of this character having suitable arrestor or stop elements for stopping or releasing the alarm winding means to open and close an electric circuit, the construction of said elements and co-acting means of the rotary switch mechanism being such that said arrestor members will be automatically moved to neutral positions by actuation of the alarm winding key in winding direction so that the clock may be subjected to its normal alarm winding operation without any adjustment of the switch or stop mechanisms, and permitting when in such neutral positions the complete or repeat operation of the alarm mechanism.

With these and other objects in view, which

will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is an elevation of the assembly.

Fig. 1a is a diagrammatic view of the contacts and wiring diagram.

Fig. 2 is an elevation of the switch mechanism with cover removed.

Fig. 3 is a section on line 3—3 of Fig. 2.

Fig. 4 is a section on the line 4—4 of Fig. 2.

Fig. 5 is a section on the line 5—5 of Fig. 3.

Fig. 6 is a similar view to Fig. 5 with the stop or arrestor elements in different positions.

Fig. 7 is a section on the line 7—7 of Fig. 2.

Fig. 8 is a detail of one of the movable arrestor elements.

Fig. 9 is a section on the line 9—9 of Fig. 2.

Fig. 10 is a view similar to Fig. 6 showing the form applicable to clocks having a left hand wind.

Fig. 11 is a view similar to Fig. 9 showing a modified form of arrestor and detachable handle.

Fig. 12 is a view similar to Fig. 9 showing a modified form of shaft construction.

The switch mechanisms of this general character with which I am familiar have proven deficient in many respects, such as being difficult to install, complex in construction, expensive to produce, and not adaptable to different types of clocks without material change to existing structures, and it was to overcome such disadvantages and to provide a time switch simple in construction, of a size and configuration presenting a pleasing appearance and easily installable without marring the appearance of the clock,

adapted to utilize the clock alarm winding key, so constructed that the alarm mechanism may be normally wound and unwound as fully and completely as if the switch was not installed, means in connection with the winding key to at all times clearly indicate the position of the switch, and marker means for determining the initial setting of the switch, movable arrestor elements for stopping the alarm mechanism to put the current on or off or to stop moving parts

while current is off, to permit continuous or repeat operation of the alarm mechanism, and the construction of the arrestor elements and co-acting switch mechanism being such that operation of the winding mechanism in winding direction will automatically move said elements

to neutral position irrespective of their setting and which permits normal winding of the alarm mechanism without regard to the switch mechanism or position of the arrestor elements, said arrestor elements adapted to control the alarm mechanism in unwinding direction or counter-clockwise to effect making or breaking of the circuit to start or stop electrical appliances, turn on or off lights, etc., according to a predetermined time setting as desired.

In the illustrated embodiment characterizing this invention there is shown conventional alarm clock A, in the present instance of the "Big Ben" type, and my improved time switch mechanism B adapted to be maintained thereon in conjunction with the alarm, as clearly shown in Fig. 1. In the present instance the casing 1 of switch B is substantially pear-shaped in configuration and is formed with an annular hollowed out portion 2 terminating in an elongated or stem portion 3, said casing being preferably constructed of an insulating material. Said casing 1 is adapted to be suitably mounted on a base plate 4 extending beyond the edge of the casing and terminating in an extension 5 formed with a central opening 6 adapted to receive the clock hand winding knob 7 and is perforated to receive the three screws 8, the normal function of which is to maintain the rear face or bell portion 9 attached to the rear of the clock A. It will be understood that said clock includes the conventional winding key 10 and alarm winding key 11 as well as the alarm setting knob 12. In order to support the switch mechanism B out of contact with the rear face or bell 9 so as not to deaden or interfere with the sounding of the alarm, portion 5 of base plate 4 is of a greater thickness as at 13 than the rest of the plate, or if the plate and extension are of the same thickness the extension may be formed with a plurality of lugs corresponding to the thickness 13.

The casing or housing is formed with a central opening 14 and with an integral collar or boss 15 extending above the bottom surface 16 of the casing. An annular slot 17 is formed in the inner surface of casing wall 18 adjacent bottom 16 for a purpose hereinafter more fully appearing. The stem portion 3 is formed in its end with a countersunk opening 19. A pair of contact elements 20 formed with curved portions 21 terminating at one end in straight plug portions 22 and with diametrically opposite lateral inwardly projecting contact plates 23, are embedded in the upper surface 24 of casing wall 18 with the plug ends 22 extending within opening 19 for engagement with corresponding openings in the plug-socket 25 connected to one end of electric wires 26 and 27 having their other ends connected to a suitable source of electrical energy when said plug 25 is inserted in opening 19 as clearly shown in Fig. 1.

Normally the key 11 is threadedly mounted on the alarm winding shaft 11'. In order to utilize the key 11 for winding the alarm when the switch B has been positioned it is only necessary to extend or lengthen the shaft 11' which is accomplished by forming a shaft section 28 square in cross section with a threaded opening 29 in one end for engagement with the threaded end of said shaft 11', and a shaft section 30 complementally bored as at 31 for telescopic engagement with the free squared end of section 28 and extending beyond the bottom surface of casing 1, its opposite end extending

10 through opening 32 to a point substantially flush with the outer surface of casing top 33 and terminating in a reduced threaded end post 34, corresponding to the threaded end of shaft 11', and adapted to be engaged by the internally threaded shank 11a of key 11 thereby forming a continuation of shaft 11' as will be well understood. The casing top 33 is detachably secured to casing wall 18 by the threaded screws 35. Interposed between shaft 30 and key shank 11a is a washer 36.

15 Integrally or otherwise mounted on shaft section 30 is an arrestor plate 37 terminating in a point 38, one edge of the plate adjacent said point being formed with a straight edge 39 and the opposite edge of the point curved as at 40, said plate 37 seating on boss 15 and end 38 adapted to travel in the slot 17 as clearly shown in Fig. 3. A perpendicular slot 41 is formed in wall 18 intersecting slot 17 to permit the insertion of end 38 in slot 17 as will hereinafter more fully appear. Mounted on the opposite end of plate 37 is an insulating block 42 on which is mounted the rotatable contact member C comprising superimposed plate members 43 separated at their opposite ends as at 44 forming a pair of end contacts 44' to engage opposite sides of the stationary diametrically opposed contact plates 23 when in bridging relation therewith and to 20 permit passage of the plates 23 therebetween during rotary movement of said contact member C, as will be well understood. The rotary contact C is mounted on block 42 by screws 45 which do not extend beyond the lower surface of said block and which effect binding engagement of the plates 43 with each other central of their 25 length.

20 The wall 18 of casing 1 is formed with a pair of spaced perpendicular bored openings 46 and 47 extending through and beyond slot 17 to a point 48 as clearly shown in Fig. 7. The cylindrical rotary switch arrestor elements 49 and 50 are adapted for insertion in the respective openings 46 and 47 and are formed adjacent their 45 lower ends with crescent-like cut-out portions 51 and the off center or eccentric stop portions 52 formed with a cam surface 53. Said arrestors 49 and 50 are provided with handles 53 and 54 integrally or otherwise connected to their upper 50 ends and extending laterally therefrom in substantial alignment with the crescent cut-out portions 51 and adapted to project through openings 55 formed in the flange 56 of top 33 and are of such a width that the end walls thereof will 55 constitute stops for limiting the arcuate movement of the handles in both directions as will hereinafter more fully appear.

When the handles 53 and 54 are moved counter-clockwise or to the left to the limit of their 60 movement so that the cut-out portions 51 are in alignment with and constitute continuations of slot 17, arrestor plate 37 may freely move in either clockwise or counter-clockwise directions, but when for instance, handle 54 is moved in a 65 clockwise or right hand direction to the limit of its movement as shown in dotted line b, the eccentric stop 52 is positioned to interrupt slot 17 and operates to stop arrestor plate 37 when rotating in anti-clockwise direction and which 70 stops the rotation of the alarm mechanism and maintains switch C in bridging alignment with stationary contacts 23 to close the electrical circuit through the switch, as will directly be described, and if handle 54 is to the left in open position and handle 53 is in its right hand posi-

tion, plate 37 will continue in a counter-clockwise movement and be arrested when it engages stop 52 of arrestor 49 to maintain the contact C in circuit opening position, and the lights, etc., off.

The above description refers to the ordinary alarm clock wherein the winding key is rotated to the right or clockwise direction. However, where clocks are wound in an anti-clockwise direction, the modified form of switch mechanism illustrated in Fig. 10 is identical to that previously described except certain parts are reversed to adapt the device to clocks having a left or counter-clockwise wind.

In this form the stop 52a will be positioned to the left and the opening 51 will be to the right and the arrestor plate 37a will be reversed so that the curved edge 40 will be on the left hand side and the straight edge 39 will be to the right, that is, reversed as to the form shown in Figs. 5 and 6. In the form illustrated in Fig. 10 the key 11 will be turned in a counter-clockwise direction to wind the alarm mechanism and to unwind will move in a clockwise direction to engage stop 52 to arrest the movement of the rotary switch contact C. In both forms of the invention if it is desired that the screws 45 extend through arrestor plate 37 the same may be provided with bushings of insulating material 57 so that there will be no short circuit of the electric current during the passage through the rotary switch mechanism.

It will thus be apparent that the device forming the subject matter of this invention may be applied to clocks having a left hand wind by simply reversing the parts above referred to.

With further reference to the wiring diagram, it will be noted that one end of the wires 26 and 27 are connected to plug-socket 25, their other ends connected to a male portion 58 connected to a female portion 59 of an electrical connection to which is connected wires 60 and 61 of a lamp D, the wire 27 being severed intermediate its length and the severed ends 62 and 63 being connected to the plug portion 64 of a socket portion 65, said socket portion 65 being connected by wires 66 and 67 to a source of electrical energy as at 68, so that the circuit will be completed through conductor 66, socket portion 65, plug 64, conductor 27, connections 58, 59, wire 60, lamp D, wire 61, connections 59, 58, wire 26, plug 25, contact 21, contact plate 23, switch C, contact plate 23, contact 21, plug-socket 25, conductor 27, connections 64, 65, and conductor 67, back to source 68.

Suitably secured to the alarm winding key 11 is a pointer strip 69 positioned in substantial alignment with the rotary switch mechanism C so that the on and off positions of said switch mechanism is indicated, said pointer or indicator 69 co-acting with a marking 70 carried by the upper surface of top 33 of casing 1 to effect the initial setting of the switch mechanism with respect to the arrestors 49 and 50 so that when said rotary switch is released by the alarm mechanism in accordance with a predetermined time setting, said mechanism will be in position to engage the respective arrestors in accordance with their predetermined setting to turn on or off lights or other appliance as desired.

It will be noted that while in the present instance the device B is shown to be suitably supported on a base plate 4 terminating in an extension 5 constructed with perforations to receive the screws 8 carried by an alarm clock of 75

the "Big Ben" type, it is to be understood that plate 4 and extension 5 may be modified to adapt its application to other alarm clock constructions without departing from the scope and spirit of this invention.

It will thus be observed that when the device B has been installed on an alarm clock all that is necessary to electrically hook up the device is to plug in the portion 64 with portion 65 connected to a source of electrical energy, connect part 58 with part 59 connected to a lamp, radio, electric motor, and the like, and connect plug-socket 25 with plug ends 22 of the switch mechanism, wind the alarm mechanism by key 11, set the time alarm and arrestors 49 and 50 to respective current on or off positions, set the pointer 69 in alignment with marking 70, and when the alarm mechanism is released the rotary switch mechanism C will be moved to circuit opening or closing positions in accordance with the predetermined time setting.

In order to further facilitate the setting of the arrestor elements 49 and 50 to effect their smooth operation irrespective of the exact location of the openings 46 and 47 and whether the alarm wind is to the right or to the left, it may be found desirable, as shown in Fig. 11, to form said arrestors 49 and 50 adjacent their upper or free ends with a series of spaced openings 11, handle 54b being detachable and adapted for suitable engagement with a selected opening as desired.

Further, as illustrated in Fig. 12, if desired, shaft section 30a may be formed with a cylindrical opening 72 communicating with squared bore 31a, and a cylindrical shaft section 73 may be integrally connected to and form a continuation of squared shaft section 28a adapted to extend through and beyond opening 32a and terminate in key portion 74. Thus the sections 28a, 73 and portion 74 constitute a unitary key structure adapted for threaded connection with shaft 11 to form a continuation thereof and when inserted in shaft 30a form a combined unitary structure. The opening 31a is so positioned that the arrestor plate 37 extends at right angles to opposite sides of portion 28a, so that when the key is inserted in opening 31a portion 74 will be in alignment with end 38 of plate 37 constituting a pointer 69a for determining and positioning said plate, similar to key 11 and pointer 69, with respect to marking 70.

While the operation of the device would seem to be clear from the above description it might be well to further state that when the device is operatively positioned on an alarm clock and the alarm mechanism wound with pointer 69 in alignment with indicating marker 70, it being understood that the alarm mechanism has been set to operate at a predetermined time, and it is desired that the lamp D be lighted the arrestor handle 54 of arrestor 50 is positioned to the right so that the arrestor or stop portion 52 will be positioned in slot 17 so that when the alarm mechanism and switch C is released rotary movement thereof will be arrested when plate 37 engages portion 52 and switch C will be maintained in bridging or circuit closing position with respect to stationary contacts 23 to complete the circuit through and light said lamp D as hereinbefore described.

When it is desired that the electrical circuit through lamp D remain closed and the light on, the initial operation is the same as above described except the switch member C is held in

bridging relation with contacts 23 by the alarm mechanism. Handle 54 is moved in anti-clockwise or left-hand direction to its limit of movement aligning slot 51 with slot 17 and handle 53 of arrestor 49 is moved to its limit of movement to the right so as to interrupt slot 17 by stop 52, and with this setting, when the alarm mechanism is released in accordance with the predetermined time setting effecting rotation of the rotary switch member C the circuit through said switch is broken and plate 37 passes arrestor 50 and engages stop 52 of arrestor 49 arresting the rotary movement of the alarm mechanism and switch member C and maintaining the circuit broken and lights off.

It is to be noted that the mounting of the time switch device constituting the instant invention on a conventional alarm clock does not in any way affect or interfere with the operation of the clock in its normal manner and to effect this end all that is necessary is to position the handles 53 and 54 at the limit of their movement in left or anti-clockwise directions so as not to interrupt slot 17 and, when so positioned, the rotary movement of the alarm mechanism in winding and unwinding directions and the continuous or repeat sounding of the alarm may be effected as freely and completely as if the device B was not carried by or connected to the clock.

It will be especially observed that in order to prevent damage to the switch mechanism the construction of the arrestors 49 and 50 and the arrestor plate 31 is such that irrespective of the position of the eccentric stop portions 52, when the alarm and switch mechanism is rotated in clock winding or clockwise direction plate 37 will effect automatic movement of arrestors 49 and 50 to neutral or non-slot interrupting positions by the engagement of the curved edge 40 with cam face 53 or the edge of portions 52 so that irrespective of the position of said arrestors the alarm mechanism may be wound the same as if the device was not installed and without any damage to the switch mechanism.

In view of the above it will be apparent that I have provided a time switch mechanism simple in construction, comprising few parts, easily installed on an alarm clock without change to existing structure, easily connected to electric light, radio, or other appliance to be controlled, so constructed as not to interfere with the normal winding operation of the alarm mechanism, manufactureable at a negligible cost, pleasing in appearance, and efficient for the purposes intended.

Although in practice I have found that the form of my invention illustrated in the accompanying drawings and referred to in the above description as the preferred embodiment is the most efficient and practical, yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. An electric time switch including spaced stationary contacts, a rotary contact member adapted to be driven by a clock alarm mechanism including a pair of rotary contacts, said

member being normally rotatable in an unwinding direction, arrestor elements, each of said elements having neutral and arrestor positions, one element when in neutral position adapted to permit free rotation of said rotary contact and when in the remaining position adapted to arrest the movement of the contact member with its contacts in bridging relation with said stationary contacts to close an electric circuit, the other element when in neutral position permitting free rotation of said rotary member with its contacts and when in its remaining position adapted to arrest the movement of said rotary contact out of engagement with said stationary contacts to maintain the electrical circuit open, means in connection with said arrestor elements whereby rotation of the rotatable member in a winding direction automatically moves the arrestor elements to their neutral position to permit free rotation of said rotary member in either direction without regard to the initial setting of said arrestor elements.

2. An electrical switch control comprising a casing, a pair of stationary contact elements carried by said casing having opposed stationary contacts adjacent one end and terminating at their free ends in plug contact members, a sectional shaft means extending through said casing, a rotary switch contact member mounted on said shaft and normally rotatable in an unwinding direction, said shaft terminating at one end in a stem, stem winding means attached to said stem, driving means for the shaft, said driving means being releasable in accordance with a predetermined time setting, arrestor means manually settable to cooperate with said rotary switch member to arrest its movement in bridging relation with said stationary contacts, and additional arrestor means manually settable for arresting movement of said switch to maintain the same in non-bridging contact, both of said arrestor means being automatically operable irrespective of their setting to permit uninterrupted rotary movement of said switch when said alarm winding shaft is rotated in alarm winding direction whereby the alarm winding mechanism may be wound in the usual manner with the winding key without regard to said electrical switch control device.

3. Switch means for controlling an electric circuit by the alarm winding shaft of a normal alarm clock, comprising a casing mounted on said clock, a winding key shaft means extending through said casing, and adapted to be connected to the alarm winding shaft so as to rotate therewith, a switch member having opposite contacts mounted on said shaft, a pair of opposed stationary contacts extending within said casing and adapted for co-action with said rotary contacts, a pair of arrestor elements carried by said casing, and an arrestor plate mounted on said shaft adapted to engage one of said elements to arrest the rotation of said switch when in bridging relation with the stationary contacts and adapted to engage the other arrestor plate to arrest the rotary movement of said switch and maintain the same in non-bridging relation with said stationary contacts, said arrestor elements being movable to positions permitting the free rotation of said arrestor and switch members in alarm winding and unwinding directions.

4. A time controlled electrical switch adapted for connection with an alarm clock including a casing, means for securing the casing to the clock spaced therefrom so as not to interfere with the

normal sounding of the alarm, an adaptor means connected with the threaded end of the clock alarm winding shaft, a switch mechanism including a rotary member in said casing, means extending through the casing and connecting the rotary member with the adaptor, said means projecting outwardly through the casing at the other end for receiving the winding handle normally carried by said alarm winding shaft, a pair of opposed stationary contacts carried by said casing for co-operation with said rotary contacts to make and break an electrical circuit through said rotary switch, an arrestor plate connected to said rotatable switch member, a pair of arrestor elements carried by said casing and having switch arresting and neutral positions, and said switch member and arrestor plate being normally rotatable in unwinding direction, said arrestor plate engageable with one of said elements to arrest its movement when in bridging relation with said stationary contacts to close an electrical circuit therethrough and when said arrestor element is in neutral position the contact plate is adapted to engage the other element to maintain said switch in circuit opening position, said elements being movable to non-arresting positions to permit free rotation of said rotatable switch member in winding and unwinding directions.

5. Switch mechanism for controlling an electric circuit by the alarm winding shaft of a normal alarm clock, comprising a casing mounted on said clock, a shaft means extending through said casing, one end adapted for connection with the alarm winding shaft so as to rotate therewith, the other end carrying a winding key structure, a rotary switch having opposite contacts adapted to normally rotate in an unwinding direction carried by said shaft within said casing, a pair of opposed stationary contacts adapted for coaction with said rotary contacts, arrestor means carried by said casing, said means having arresting and neutral positions, arrestor engaging means associated with said rotary contact coacting with said arrestor means to arrest said rotary contact in bridging relation with said stationary contacts or in non-bridging relation depending upon the position of said arrestor means, a marking predeterminedly positioned exterior of said casing, said key structure adapted to rotate with said shaft exterior of said casing indicating the position of said rotary switch contact member and co-acting with said marking to effect initial setting of said rotary switch with respect to said arrestor means, characterized in that said arrestor engaging means is adapted to co-operate with said arrestor elements whereby rotation of said rotary switch member in winding direction automatically effects movement of the arrestors to their neutral positions, permitting free rotation of said alarm mechanism and switch contact member in both directions.

6. An electrical time switch including spaced stationary contacts, a rotary contact member adapted to be driven by a clock alarm mechanism and including a pair of rotary contacts, said member being normally rotatable in an unwinding direction, arrestor elements having cam stop means, means for predeterminedly setting said stop means, said latter means having stop and non-stop positions, an arrestor plate adapted to travel with said rotary contacts and adapted to engage one of said stop elements, when in stopping position, to arrest the rotation of said rotary contacts in bridging relation with the sta-

tionary contacts, and to engage the stop means of the other arrestor, when in stopping position, to arrest the movement of said switch in non-bridging relation with respect to said stationary contacts, the stop means of said arrestor elements being automatically movable by said arrestor plate, when moving in winding direction, to positions permitting the free rotation of said arrestor and rotary contacts in alarm winding direction whereby said rotary elements may be freely rotated in either direction.

7. A switch means for controlling an electric circuit by the alarm winding shaft of a normal alarm clock comprising a casing mounted on said clock, shaft means extending through said casing and adapted to be connected to the alarm winding shaft so as to rotate therewith, a switch member having opposite contacts mounted on said shaft means, a pair of opposed stationary contacts extending within said casing and adapted for co-action with said rotary contacts, a pair of settable arrestor elements carried by said casing including stop means, said means having stop and non-stop positions, an arrestor plate carried by said shaft means adapted to engage one of said stop elements, when in stopping position, to arrest the rotation of said switch in bridging relation with the stationary contacts, and adapted to engage the stop means of the other arrestor when in stopping position to arrest the rotary movement of said switch and maintain the same in non-bridging relation with said stationary contacts, the stop means of said arrestor elements by rotation of the key winding shaft in winding direction being automatically movable to positions permitting the free rotation of said arrestor and switch members in both directions, and adjustable means for varying the setting of said stop means to permit automatic movement of said stop means by said arrestor plate in winding direction irrespective of whether the winding direction of the alarm mechanism is to the right or to the left.

8. An electrical time switch including a pair of spaced contacts, a rotary contact member adapted to be driven by the alarm mechanism of a clock in alarm winding direction and having oppositely positioned contacts, arrestor means to predeterminedly stop the movement of said contacts, said arrestor means having neutral and circuit making and breaking positions, an arrestor plate connected to said rotary member and adapted to engage said first mentioned arrestor means when in circuit making position to arrest the movement of said rotary member in bridging relation to said stationary contacts to close an electrical circuit and when in circuit breaking position adapted to arrest and maintain said contact element with the rotary contacts in circuit breaking position to maintain the circuit open, said arrestor means being automatically moveable to neutral position by said arrestor plate upon actuation of the alarm mechanism and said rotary member in alarm winding direction.

9. In combination with an alarm clock having an alarm winding shaft projecting to the outside of the clock; of a unit fixedly maintained on said clock comprising a casing, an electrical mechanism within the casing including stationary contacts and a rotary switch structure connected to said alarm winding shaft for opening and closing an electrical circuit, said rotary structure projecting at its opposite end beyond said casing and adapted for connection with a winding key, an arrestor member carried by and rotatable

with said rotary switch, arrestor elements carried by said casing having arresting and neutral positions and manually settable to arrest said arrestor member when moving in unwinding direction to respectively close and open said circuit as desired, said arrestor elements being automatically operable to neutral position irrespective of their set positions by said arrestor plate upon the normal actuation of said alarm winding shaft in winding direction whereby the conventional winding of the alarm mechanism is effected without regard to said unit.

10. In combination with an alarm clock having an alarm winding shaft projecting to the outside of the clock; of a unit fixedly mounted on said clock overlying said shaft comprising a casing having an annular recess, an electrical mechanism within the casing including stationary contacts and a rotary switch structure connected

5 to said alarm winding shaft for opening and closing an electrical circuit and projecting at its free end beyond said casing, an arrestor member operable in said recess and carried by and rotatable with said rotary switch, arrestor elements carried by said casing, said elements being manually settable to interrupt said recess and arrest said arrestor member when the latter is moving in unwinding direction to respectively close and open said circuit as desired, said arrestor elements automatically operable to non-recess interrupting position irrespective of their set positions by the engagement of said arrestor plate upon the normal rotation of said alarm winding shaft in winding direction, whereby the conventional winding of the alarm winding mechanism is effected without regard to said unit.

JOEL HENRY HENDRIX.
